UNITED STATES PATENT OFFICE.

EARL M. STAPLETON, OF OKLAHOMA CITY, OKLAHOMA.

CARRIER.

Application filed December 5, 1923. Serial No. 678,702.

To all whom it may concern:

Be it known that I, EARL M. STAPLETON, a citizen of the United States, and a resident of Oklahoma City, in the county of 5 Oklahoma and State of Oklahoma, have invented certain new and useful Improvements in Carriers, of which the following is a specification.

This invention relates to carriers adapted 10 for use on automobiles and other vehicles.

Briefly stated, an important object of this 15 invention is to provide a carrier having novel means to receive and support cooking and eating equipment in such a manner that the equipment will not rattle or break, as 20 a result of the movement of the vehicle over rough roads.

A further object is to provide a carrier 25 wherein the end walls of the same may be swung to horizontal position to form tables at opposite sides of the vehicle, and which tables are formed with hollow compartments adapted to receive such articles as knives, books, packages and more or less flat cooking utensils.

A further object is to provide a carrier 30 of the class specified which may be conveniently applied to a motor vehicle, and which will not in any way mar the appearance of the vehicle.

A further object is to provide a carrier 35 for motor vehicles which is of highly simplified construction, durable in use, and cheap to manufacture.

Other objects and advantages will be apparent 40 during the course of the following description.

In the accompanying drawings forming a part of this construction, and in which 45 like numerals are employed to designate like parts throughout the same,

Figure 1 is a perspective of the improved carrier applied and being in closed position,

Figure 2 is a plan view of the same, parts 45 being shown in section,

Figure 3 is a perspective of the improved carrier in open position,

Figure 4 is a longitudinal sectional view 50 through the improved carrier in its closed position,

Figure 5 is a vertical transverse sectional view taken on line 5—5 of Figure 4,

Figure 6 is a horizontal sectional view 55 taken on line 6—6 of Figure 4,

Fig. 7 is a fragmentary perspective of the

carrier in open position, the view illustrating an ice-box embodied in the invention,

Figure 8 is a perspective illustrating the sections at one end of the carrier partly 60 open to display the articles carried within the shallow compartments of the same.

Figure 9 is a fragmentary plan view illustrating a cook stove and the supporting means therefor.

In the drawing wherein for the purpose of illustration is shown a preferred embodiment of the invention, the numeral 5 designates a vehicle, the rear portion of which is provided with a plurality of brackets 70 adapted for supporting a spare tire 7. Figure 1 illustrates that the arms or brackets 6 also support a platform 8 upon which a chest or carrier 9 of rectangular formation is mounted. Suitable fastening devices 75 may, of course, be employed for securing the carrier or chest in position and by way of illustration, in Figure 4 I have illustrated fastening devices 10 to secure the chest in 80 position.

The sides and the top of the carrier are closed while the ends of the carrier are provided with combined doors and tables 12 and 13 horizontally hinged at their lower ends as indicated at 15, to the lower end of 85 the carrier so that the same may be swung either to an upright position for use as doors, or swung in horizontal position for use as tables.

Each combined door and table consists of 90 a plurality of similarly constructed sections hingedly connected at their longitudinal edges as indicated at 18.

More specifically each door section is provided with side and end flanges 37 to which 95 the hinges 18 are connected and with reference to Figures 4 and 8, it will be seen that the side and end flanges 37 define shallow compartments adapted for the reception of various more or less flat articles used in 100 cooking and in touring. The articles may be held in place by clips 3 secured to the undersides of the several sections of the combined doors and tables. Such articles as a cook-book, a salt can, a match box, soap, a first-aid kit, an ax, a butcher knife, a cake turner, a towel, or a can opener may be held in position by means of the clips and when in place the articles are securely and positively held against loss or against 110 rattling.

Each section of each combined door and

table is fastened and reinforced by means of a longitudinally extending tube 24, securely welded at its ends to the end flanges 37. Figure 8 illustrates that the tubes 24 are located between the longitudinal edges of the side flanges 37 and securely brace the table and prevent twisting of the same. By reason of this construction, the sections when extended as illustrated in Figure 3 form an extremely rigid table.

There are two sections of the combined doors and tables 13 and these are designated by the numerals 19 and 20, while the combined door and table 12 consists of three sections designated by the numerals 20', 21 and 22, and it will be seen that the table 12 is somewhat greater in area than the table 13 to allow a comparatively large number of people to comfortably seat themselves about the table. The sides of the several tables are entirely free except for supporting members 25 employed for securing the table in horizontal position. The supporting members 25 may be of any character such as collapsible sectional braces, flexible chains, or one-piece links. Preparatory to swinging the several sections to upright position, the links, are of course, collapsed and may be positioned in the carrier or in some of the shallow compartments of the several table sections as shown in Figure 8. This figure illustrates that one or more of the links 25 may be secured in an inoperative position by means of clips 26. Attention is directed to the fact that when the sections are swung to their closed position, the side and end flanges 37 swing into edge to edge contact to enclose the articles within the several compartments and thereby prevent the loss of the same. The doors are held in upright positions and the sections of the doors are prevented from swinging outwardly by locking arms 2 extended through openings 17 in the sections and engaged by locks 17 carried by the outermost sections. By reason of this construction unauthorized access to the several shallow compartments and the interior of the carrier is prevented. It is thus seen that for each combined door and table a single lock is provided to hold the door in elevated position and to hold the several sections of each door in a closed position.

Figure 3 illustrates that when the door 13 is opened a plurality of article-containing receptacles 30 are exposed. The article-containing receptacles 30 are closely arranged in one end of the carrier and a partition or shelf 31 is extended across the carrier to support the uppermost series of article-containing receptacles. The space above the shelf 31 may be occupied entirely by various article-containing receptacles and as illustrated in Figure 4 collapsible stools 32 may be positioned in the carrier beneath

the partition 31 along with certain article containers or cooking utensils. Of course the space in the carrier from the door 13 to the upright partition 1 is occupied by various containers et cetera, so constructed and arranged that no rattling or unrestrained movement of the same is permitted.

Figure 9 illustrates that a stove 33 is secured to the section 20 of the door 13 by fastening rivets 33' which extend through longitudinal slots 34' in the bottom of the stove. The ends of the slots 34' are enlarged to permit of the passage of the heads of the rivets or fasteners 33' whereby the stove may be moved longitudinally of the section 20 or completely detached. Of course it is desirable to move the table 33 longitudinally of the section 20 when preparing to close the carrier. A fuel container 36 of any suitable character is connected to the stove 33 and may be detached when it is desired to close the carrier.

Figures 4, 6, and 7 illustrate that one end of the carrier is provided with an ice-box 40 insulated by laminations of fiber or suitable material 50 to effectively exclude the heat of the sun and to permit the ice 43 to maintain the contents of the ice-box in a chilled condition. The door 45 of the ice-box may be conveniently opened to expose the contents of the box and attention is directed to the fact that when the door 12 is in its closed position access to the box is impossible. Also the sections of the door 12 provide effective insulation for the front of the ice-box. However, it is important to note that the opening of the door 12 does not expose the contents of the ice-box and thus the contents of the box are maintained in the proper condition at all times.

Figure 4 illustrates that a water-cooler 44 is arranged in the bottom of the ice-box and is provided with an upstanding branch 47 in which a quantity of water is arranged. The water-cooler may be filled from time to time by means of a funnel 42 connected to the upper end of the branch 47. It will be seen that the tube of the funnel 42 is long enough to permit the funnel to be arranged exteriorly of the ice-box when it is desired to fill the water-cooler. The water may be discharged from the water-cooler by a spigot 46.

The ice 43 not only keeps the water in the water-cooler 44 cool, but also maintains the articles upon the trays 41 in a chilled condition.

In summarizing it will be seen that no collapsible legs or braces are employed to support the several tables from below, and consequently, it is not necessary to stop the vehicle upon level ground preparatory to opening the doors 12 and 13 for use as tables. Also the absence of legs supporting the table from below enables the carrier to

be very compactly folded when not in use. The supporting members 25 do not seriously interfere with the free use of the several tables, and a comparatively large number 5 of people may gather about the several tables.

In carrying out the invention a wash-basin 60 may be secured to the combined door and table 12 as indicated at 61. Of course the wash-basin 60 may be detached when it is desired to close the carrier.

With reference to the foregoing description, taken in connection with the accompanying drawings, it will be seen that the doors 12 and 13 may be quickly swung to horizontal position for use as tables without first loosening straps, cords or the like, and without first removing other articles. The members 12 and 13 may at any time be 15 swung to horizontal position to completely expose the containers 30 and to permit 20 access to the ice-box.

Particular attention is invited to the fact that the opening of one of the doors does 25 not expose the contents of the carrier at the opposite side of the central partition 1, and one of the doors may be opened or closed without reference to the other door, or without disturbing the contents of the 30 several compartments.

Also, a carrier constructed in accordance with this invention may be applied to a vehicle without altering the construction of the same and without in any way marring 35 the appearance of the vehicle, all of which contributes to the desirability of the carrier.

Particular attention is directed to Figures 4 and 6 which illustrate that the edge 40 portions of the combined closure and table section at the ends of the body are formed with beads which flatly contact with each other and which close the space between the sections. Also, the inner section of each 45 set of sections has its major portion snugly received within the body so a comparatively tight fit is provided between the sections and the body to render the touring chest dust proof and to prevent the same from rattling. This also provides a neat connection 50 between the sections and the body of the chest.

Having thus described my invention, what is claimed is:—

55 1. A chest for use in touring comprising a body having means whereby the same may be secured to an automobile a closure consisting of hingedly connected inner and outer sections having their edge portions 60 formed with flanges having beads adapted to flatly contact with each other to close the space between the sections, the inner section and the associated flanges being snugly received in said body to provide a 65 close contact between the closure and the

body, one of the sections being horizontally hinged to the body whereby the sections may be swung to horizontal position for use as a table.

2. A chest for use in touring comprising 70 a body having means whereby the same may be secured to an automobile, a closure consisting of hingedly connected inner and outer sections having their edge portions formed with flanges having beads adapted 75 to flatly contact with each other to close the space between the sections, the inner section and the associated flanges being snugly received in said body to provide a close contact between the closure and the body, one of the sections being horizontally hinged 80 to the body whereby the sections may be swung to horizontal position for use as a table, and a container in said body and insulated by the space between the sections 85 when in closed position.

3. A chest for use in touring comprising 90 a body having means whereby the same may be secured to an automobile, a closure consisting of hingedly connected inner and outer sections having their edge portions formed with flanges having beads adapted 95 to flatly contact with each other to close the space between the sections, the inner section and the associated flanges being snugly received in said body to provide a close contact between the closure and the body, one of the sections being horizontally hinged 100 to the body whereby the sections may be swung to horizontal position for use as a table, and a container in said body and insulated by the space between the sections 105 when in closed position, and a closure for said container located immediately behind said sections and within said body.

4. A carrier comprising a rectangular body, doors horizontally hinged at their lower ends to said body for closing the same, consisting of a plurality of sections 110 hingedly connected, said sections being adapted to be swung to open position to form tables, flexible supports connecting the sections to said carrier, said sections having their ends and edges formed with flanges defining shallow compartments 115 adapted for the reception of articles, and fastening means within said shallow compartments to securely support articles.

5. A carrier for motor vehicles, comprising 120 a platform adapted for attachment to a motor vehicle, a carrier of rectangular formation mounted on the platform and having its ends provided with horizontally hinged doors, each of said doors consisting 125 of a plurality of hingedly connected sections adapted to be positioned horizontally to define tables and adapted to be folded together when the door is swung to closed position, said sections being provided with shallow compartments adapted for the re- 130

ception of articles, said compartments being closed when the door is closed by the adjacent sections.

6. A carrier for motor vehicles, comprising a platform adapted for attachment to a motor vehicle, a carrier of rectangular formation mounted on the platform and having its ends provided with horizontally hinged doors, each of said doors consisting of a plurality of hingedly connected sections adapted to be positioned horizontally to define tables and adapted to be folded together when the door is swung to closed position, said sections being provided with shallow compartments adapted for the reception of articles, said compartments being closed when the door is closed by the adjacent sections, and a partition arranged in the carrier and defining upper and lower compartments adapted for receiving articles employed in cooking.

7. A carrier for motor vehicles, comprising a platform adapted for attachment to a motor vehicle, a carrier of rectangular formation mounted on the platform and having its ends provided with horizontally hinged doors, each of said doors consisting of a plurality of hingedly connected sections adapted to be positioned horizontally to define tables and adapted to be folded together when the door is swung to closed position, said sections being provided with shallow compartments adapted for the reception of articles, said compartments being closed when the door is closed by the adjacent sections, a partition arranged in the carrier and defining upper and lower compartments adapted for receiving articles employed in cooking, and a cook stove fixed to one of the sections of one of said doors.

8. A carrier for motor vehicles, comprising a platform adapted for attachment to a motor vehicle, a carrier of rectangular formation mounted on the platform and having its ends provided with horizontally hinged doors, each of said doors consisting of a plurality of hingedly connected sections adapted to be positioned horizontally to define tables and adapted to be folded together when the door is swung to closed position, said sections being provided with shallow compartments adapted for the reception of articles, said compartments being closed when the door is closed by the adjacent sections, a partition arranged in the carrier and defining upper and lower compartments adapted for receiving articles employed in cooking, a cook stove fixed to one of the sections of one of said doors, and an ice box received in said carrier and accessible from one end of the same.

9. A carrier for motor vehicles, comprising a platform adapted for attachment to a motor vehicle, a carrier of rectangular formation mounted on the platform and

having its ends provided with horizontally hinged doors, each of said doors consisting of a plurality of hingedly connected sections adapted to be positioned horizontally to define tables and adapted to be folded together when the door is swung to closed position, said sections being provided with shallow compartments adapted for the reception of articles, said compartments being closed when the door is closed by the adjacent sections, a partition arranged in the carrier and defining upper and lower compartments adapted for receiving articles employed in cooking, a cook stove fixed to one of the sections of one of said doors, an ice box received in said carrier and accessible from one end of the same, and a water cooler arranged in said ice box.

10. A chest for use in touring comprising a body having means whereby the same may be secured to an automobile, the closure consisting of hingedly connected inner and outer sections having their edge portions formed with flanges adapted to contact with each other to close the space between the sections, the inner section having its major portion snugly received in said body to provide a close fit between the closure and the body, one of the sections being hinged to the body whereby the sections may be swung to horizontal position for use as a table, and means connected to the sections and to the body at a point above the sections for supporting the sections when in a horizontal position.

11. A carrier comprising a body having its top and sides closed and having its ends provided with horizontally hinged doors adapted to be arranged horizontally to provide tables, said doors being provided with side and end flanges the abutting side flanges of the section being hingedly connected, and strengthening and reinforcing tubes extending longitudinally of the sections between the sides of the same and being securely connected at their ends to the end flanges of the sections whereby to limit twisting of the sections.

12. A carrier comprising a body having its top and side closed and having its ends provided with horizontally hinged doors adapted to be arranged horizontally to provide tables, said doors being provided with side and end flanges, the abutting side flanges of the section being hingedly connected, strengthening and reinforcing tubes extending longitudinally of the sections between the sides of the same and being securely connected at their ends to the end flanges of the sections whereby to limit twisting of the sections, and collapsible supporting members connected to said doors and to the end portions of the carrier.

13. A carrier comprising a body having closed sides and a closed top, combined doors

- and tables horizontally hinged to the ends of the body and consisting of sections hingedly connected at their abutting edges, certain of said sections being provided with openings, locking arms carried by said body and adapted to extend through said openings, and locks carried by the outermost sections and adapted for engagement with said locking arms, said locks forming a means for holding the doors in upright position and for holding the sections partly in contact with each other.
14. A carrier comprising a body having closed sides and a closed top, combined doors and tables horizontally hinged to the ends of the body and consisting of sections hingedly connected at their abutting edges, certain of said sections being provided with openings, locking arms carried by said body and adapted to extend through said openings, and locks carried by the outermost sections and adapted for engagement with said locking arms, said locks forming a means for holding the doors in upright position and for holding the sections partly in contact with each other, said sections being provided with shallow article-receiving compartments.
15. A carrier comprising a body having one end open, a combined door and table horizontally hinged to the carrier at the open end of the same and consisting of a plurality of sections hingedly connected at their abutting longitudinal edges, said sections being provided with side and end flanges defining shallow article-receiving compartments, clips carried by said sections for supporting articles within said compartments, the flanges of one section being adapted for edge to edge contact with the flanges of the other section when the door is in closed position whereby the contents of the several compartments are concealed, a locking arm carried by said body and extending through the inner sections of the door and having locking engagement with the outermost section of the door to hold the door in closed position and to hold the flanges of one section in edge to edge contact with the flanges of the other section.
16. A carrier comprising a body having one end open, a combined door and table horizontally hinged to the carrier at the open end of the same and consisting of a plurality of sections hingedly connected at their abutting longitudinal edges, said sections being provided with side and end flanges defining shallow article-receiving compartments, clips carried by said sections for supporting articles within said compartments, the flanges of one section being adapted for edge to edge contact with the flanges of the other section when the door is in closed position whereby the contents of the several compartments are concealed.
17. A carrier comprising a body having one end open, a combined door and table horizontally hinged to the carrier at the open end of the same and consisting of a plurality of sections hingedly connected at their abutting longitudinal edges, said sections being provided with side and end flanges defining shallow article-receiving compartments, clips carried by said sections for supporting articles within said compartments, the flanges of one section being adapted for edge to edge contact with the flanges of the other section when the door is in closed position whereby the contents of the several compartments are concealed, a locking arm carried by said body and extending through the inner sections of the door and having locking engagement with the outermost section of the door to hold the door in closed position and to hold the flanges of one section in edge to edge contact with the flanges of the other section, and means to support the combined door and table in a horizontal position.
18. A carrier of the class described comprising a body having an open end, an ice-box arranged in the open end of the carrier and having a door, and a combined door and table horizontally hinged at the open end of the carrier and consisting of a plurality of sections having side and end flanges adapted to be arranged in edge to edge contact to define an air space between the atmosphere and the ice box.
19. A carrier of the class described comprising a body having an open end, an ice-box arranged in the open end of the carrier and having a door, a combined door and table horizontally hinged at the open end of the carrier consisting of a plurality of sections having side and end flanges adapted to be arranged in edge to edge contact to define an air space between the atmosphere and the ice box, and locking means to hold the sections of the second door in closed position and thereby prevent access to the first named door.

EARL M. STAPLETON.
